GUTTER CLEANER FOR DAIRY BARN

Albert Garand, Victoriaville, Quebec, and Henri Labonté, Ste.-Sophie, Quebec, Canada

Application July 9, 1957, Serial No. 670,818

1 Claim. (Cl. 198—224)

This invention relates to farm apparatus and more particularly to means for cleaning dairy barns.

It is an object of the present invention to provide a device for cleaning the gutters of dairy barns whereby manure deposited therein may be easily and quickly removed to a central outside location.

Another object of the present invention is to provide a gutter cleaner of the above type that is operated by means of a chain having guide means for effecting movement thereof around horizontal and vertical corners to deliver the manure to a predetermined area.

Other objects of the invention are to provide a gutter cleaner bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawings, in which:

Figure 1 is a fragmentary top plan view of apparatus made in accordance with the present invention in operative use;

Figure 2 is a side elevational view of the apparatus shown in Figure 1;

Figure 3 is an enlarged transverse cross sectional view taken along line 3—3 of Figure 1;

Figure 4 is a fragmentary perspective view of a chain forming a part of the present invention;

Figure 5 is a perspective view of one of the drag blades forming a part of the present invention;

Figure 6 is a top plan view of part of the apparatus showing how a horizontal corner can be negotiated;

Figure 7 is an enlarged fragmentary cross sectional view showing certain parts of the structure shown in Figure 2; and

Figure 8 is a perspective view of a link adapter forming another part of the present invention.

Referring now more in detail to the drawing, a gutter cleaning device made in accordance with the present invention is shown in operative association with a plurality of stalls 1 arranged side by side within a stable 2 that is provided with an alley 3 and longitudinal gutter 4. An upwardly inclined outside extension 5 forms a continuation of gutter 4 so as to provide communication with the exterior of the stable. A support leg 6 maintains the outer end of the extension 5 in the raised position.

A chain composed of a plurality of pairs of links 7 pivotally connected at each end to each next adjacent link forms a support for a plurality of longitudinally spaced apart drag blades 9, each one of which is provided with a front face 9', an end face 10', an angular side face 10 and an angularly related rib 11 projecting from side face 10 and having a transversely extending hole 12 through which certain ones of the pivot pins 8 of the chain assembly extend. As is more clearly shown in Figure 7, the blades 9 are secured to the pins 8 by means of washers 13 and cotter pins 14. With the links

2

arranged in the flat position and connected by end pins 8, as shown at the left side of Figure 4, the chain may be used to turn a horizontal corner 18 formed in the gutter as shown in Figure 6. However, by using an 5 adapter square link 20, other chain links 7 may be placed in the edge position shown toward the right side of Figure 4, in which position pivot pins 15 are secured intermediate the midsections of each pair of such links so as to 10 rotatably support the drag blade 9 which is secured thereon by means of washers 16 and cotter pins 17. With this arrangement, the chain may be directed a vertical corner, such as that shown in Figure 2 by means of an idler pulley 19. With reference to Figure 8, the adapter link 20 is shown to include a transverse bore 21 15 at each end, each of which extends in a perpendicularly related direction relative to the other, so that this change in the pivotal axis of each link may be effected. The links are preferably placed in the flat position in order to reduce the filling of the space therebetween with manure during operation. However, the position may be 20 changed for turning corners, as may be required, only a few links being needed adjacent to each corner section.

The opposite ends of the chain are connected by means of a flexible cable 22 that is trained about various corner 25 pulleys 23, 24, 26 and ceiling pulleys 27 carried upon the ceiling 25 of the barn. Reciprocating longitudinal movement of the chain is obtained by a connecting rod 28 that is joined at one end to one of the pins 8 of the chain and at the other end to an endless chain 29 which 30 is driven by a motor 30, the chain being drawn in one direction when the connecting rod 28 is drawn by the upper course of the drive chain, and being driven in the reverse direction when driven by the lower course thereof. When the chain is being moved in the direction toward 35 the exterior manure pile 50 outside of the stable, the blades 9 are disposed substantially transversely of the gutter in order to scrape the bottom of the gutter and move the manure further along therein. When the chain is reciprocated in the opposite direction, the frictional 40 engagement of the blades 9 with the bottom of the gutter are operative to rotate the blades to the dotted line position shown in the drawing, wherein they are slightly inclined to the longitudinal axis of the gutter, which movement is limited by the engagement of the face 10 with the adjacent link. Thus, by continuously reciprocating 45 the chain, the drag blades 9 are operative to draw all of the manure outwardly to the central pile 50.

While various changes may be made in the detail construction, it shall be understood that such changes shall be within the spirit and scope of the present invention 50 as defined by the appended claim.

What we claim as new and desire to protect by Letters Patent of the United States is:

A gutter cleaner for dairy barns comprising, in combination, a flexible chain, means pulling said chain within 55 a dairy barn gutter for reciprocating longitudinal movement, said chain being constituted by pivotally interconnected links, the pivotal axis of certain ones of said links being at right angles to the pivotal axis of the others of said links, means guiding the parts of said chain constituted by said certain ones of said links around horizontal corners, additional means guiding the parts of said chain constituted by the others of said links around vertical corners, vertical pivot pins carried by and upstanding from said links at spaced intervals along said chain, and 60 elongated drag blades, each having an end face, an inclined side face adjacent said end face and an aperture receiving one of said pivot pins for pivotal movement of said blade in relation to said chain between an operative position at substantially right angle to the adjacent links with said end face abutting against said adjacent 65 70

links, and an inoperative position slightly inclined with respect to said adjacent links and with said inclined side face abutting said adjacent links, alternating movement of said chain in opposite direction causing pivotal movement of said drag blades between said two positions thereof. 5
